UNITED STATES PATENT OFFICE

CHARLES F. BUENTE, OF PITTSBURGH, PENNSYLVANIA, ASSIGNOR TO CONCRETE PRODUCTS COMPANY, OF PITTSBURGH, PENNSYLVANIA, A CORPORATION OF PENNSYLVANIA

REENFORCED CONCRETE PIPE

Application filed June 16, 1927. Serial No. 199,195.

This invention relates to reenforced pipe, and more particularly to a reenforced concrete pipe having the reenforcing advantageously disposed with particular reference 5 to the load normally encountered in such pipes. To this end, the reenforcing is made of a geometrical shape different from that of the pipe itself, for example, a circular pipe may have an elliptical reenforcing cage 10 therein, or an elliptical pipe may have a circular reenforcing.

Considering the load on a pipe buried in the earth, it will be seen that the concrete adjacent the inner surface will be in tension 15 at the top and bottom of the pipe and in compression at the sides, while the concrete adjacent the outer surface will be in tension at the sides and in compression at the top and bottom. With a reenforcing of different 20 configuration than the pipe, it is possible to place steel in such relation to the inner and outer surfaces that it will take care of the tension loads in the most advantageous way.

In forming an elliptical reenforcing cage, 25 I preferably utilize two generally semi-circular portions connected by short tangential elements, and form a truss across the tangential elements whereby the cage is maintained in the desired shape against the 30 springing tendency of the reenforcing rod. The longitudinal elements of the cage are preferably welded to the circular elements and are so disposed that the stress imposed by the load normally encountered by the pipe is 35 distributed over a large portion of the concrete, thereby obviating the possibility of the reenforcing rods to cut through the concrete when the rods are tensioned.

In the accompanying drawing illustrating 40 certain preferred embodiments of my invention,

Figure 1 is a cross sectional view of a circular pipe reenforced according to my invention;

Figure 2 is a sectional view taken on the line II-II of Figure 1;

Figure 3 is an enlarged sectional view of the trussed portion of the reenforcing; and

Figure 4 is a sectional view of an elliptical 50 pipe reenforced according to my invention.

Referring to the illustrated embodiment, there is shown a generally circular pipe 2 having a reenforced steel cage therein. The cage comprises a helically wound rod or wire shaped on a suitable form so as to have substantially semi-circular portions 3 connected by short tangential portions 4, the tangential portions lying at the top and bottom of the pipe. Longitudinal rods 5 are secured to the tangential elements 4, preferably by 55 welding. Truss members 6 overlie the longitudinal members 5 and are secured to such members as well as to the semi-circular portions 3. Other longitudinal members 7 serve to stiffen the cage and sustain a portion of the 60 longitudinal bending load on the pipe. The cage is preferably made by welding all intersections while the helically wound wire is still on the form. The wire usually employed has considerable spring and will tend 65 to restore the cage to circular cross-section. This tendency, however, is overcome if the truss members 6 are welded in place while the cage is supported by the form.

When a pipe is loaded with a concentrated 70 load at the top thereof, the load moment and consequently the stress along the vertical axis in the steel, is approximately in the ratio of 16 to 9, as compared with the load moment and stress in the steel along the horizontal 75 axis. If the pipe be uniformly loaded along the horizontal, these moments and stresses in the steel are equal. In actual practice, neither of these conditions ordinarily obtains, but the load near the central axis of the pipe 80 is always greater than the load at the sides of the pipe. This results in the load moment and stress in the steel along the vertical axis A-A being somewhat greater than the corresponding load moment and stress along the horizontal axis B-B. The short circumferential trussing formed by the tangential portions 4 and the truss members 6 embracing the longitudinal elements 5 provide additional strength where the greater stresses are 85 encountered.

A load imposed on a reenforced concrete pipe sets up tension stresses in the steel which tend to straighten out the transverse reenforcing members. This results in a tendency of 100

the steel to shear its way through the concrete at the top and bottom portions of the pipe with the result that the pipe fails before the steel has reached this permissible maximum stress. By anchoring the circular reenforcement to a series of longitudinal members at the top and bottom of the pipe, the steel is firmly anchored in place and the load is so distributed that the effective stress in the steel 10 may be greatly increased without danger of shearing the concrete.

In a straight concrete beam the adhesion between the concrete and steel is sufficient to prevent slipping of the concrete over the steel 15 due to change in tensional stress in the steel. When the tensional stress reaches the point where rupture of the concrete occurs, it results in a series of minute cracks which are harmless to the structure. In the curved 20 structure of a pipe the change in tension from its maximum along the vertical axis to the points of contraflexure is so great that the concrete slips on the steel with the formation, usually, of one large dangerous crack. Anchoring the circular reenforcing to a series of 25 longitudinal members prevents this slipping and rupture in the concrete occurs by the formation of a number of smaller less harmful cracks. This condition occurs only at the 30 points of maximum tension on the inside of the pipe.

As shown in Figure 2 the pipe 2 has bell and spigot ends the bell 8 being provided with circular reenforcing 9 substantially up to the face of the pipe. The longitudinal members 5 are bent outwardly and are shaped to lie adjacent the circular reenforcing 9 so that a substantially rigid cage is formed from one end of the pipe to the other even to the 35 end of the bell. By spot welding the longitudinal members 5 and 7 to the helical portions 4 and 9 a substantially rigid self-sustaining cage is formed which will maintain its shape in a molding machine.

Figure 4 illustrates an elliptical pipe 10 having a substantially circular reenforcing cage therein. The cage is formed of a helically wound rod or wire shaped to form a cage having a substantially circular cross section. The substantially circular convolutions 11 are connected by longitudinal rods 12 and 13 welded thereto. The longitudinal rods 12 are grouped together at the top and bottom of the pipe to compensate for the difference 40 in load moments about the vertical and horizontal axes. The longitudinal rods 13 stiffen the cage and also take a portion of the bending load. The reenforcing is formed into a substantially unitary structure by welding all points of intersection between the longitudinal members and the helically wound rod whereby a stiff self-supporting cage is formed capable of retaining its shape during pouring and tamping operations.

As indicated by dotted lines the pipe 10 is

provided with a reenforcing element 14 which lies in the bell of the pipe and approaches the face thereof. The longitudinal rods 12 are outwardly bent, as indicated at 15, to lie adjacent the reenforcing 14 and stiffen the same.

The pipes illustrated are provided with re-enforcing in the spigot end so far as is possible, without deflecting the reenforcing out of the shape to which it conforms within the body of the pipe which would interfere with tamping of the concrete.

Exterior indentations in the form of beads 16 show the position of the reenforcing in the interior of the pipe. When laying the pipe, therefore, it is easy to determine the correct position, so that the interior reenforcing will be disposed in the best position to take the load. While I have shown beads for accomplishing this purpose, it will be understood that any desired index may be used to show the correct position of the pipe with respect to the applied load.

While I have illustrated and described certain preferred embodiments of my invention, it will be understood that the invention is not limited thereto, but may be otherwise embodied within the scope of the following claims:

I claim:

1. A reenforced concrete pipe having a re-enforcing cage therein including a plurality of longitudinal reenforcing rods, the rods being disposed in groups at certain portions of the reenforcing whereby the pipe has increased strength about an axis thereof, and means on the exterior of the pipe for indicating the correct position of the pipe when in service.
2. A reenforced concrete pipe having transverse reenforcing members, a plurality of grouped longitudinal reenforcing rods, and truss members overlying the reenforcing rods, connected to the transverse members, the longitudinal rods being welded to the truss members and to the transverse members.
3. A reenforcing cage for concrete pipe, comprising a relatively springy member formed to non-circular contour, and truss means for resisting the spring of the member to hold it to the desired contour.
4. A reenforcing cage for concrete pipe, comprising a relatively springy wire wound to non-circular shape, and trusses secured to the wire and effective for holding it substantially to the shape in which it is wound.
5. A reenforced concrete pipe having a re-enforcing cage therein, said cage comprising a truss applied circumferentially to said cage, the outer surface of the pipe having an index for indicating the position of said truss.
6. A reenforced concrete pipe having a re-enforcing cage therein, said cage comprising a continuous helix, each turn thereof having straight portions and semi-circular portions, longitudinal members connected to said turns

at the straight portions, and truss members overlying the longitudinal members connected at their ends to the semi-circular portions.

5 7. A reenforcing cage comprising a helix having a plurality of turns, truss members secured thereto at their ends, said truss members extending substantially parallel to said turns, and a longitudinal member lying between the truss members and the turns and secured thereto.

8. A reenforcing cage for concrete pipe including a helix having a plurality of turns including substantially straight portions, and 15 truss members overlying the straight portions of said turns, the truss members being effective for maintaining the cage in substantially elliptical shape against the spring of the reenforcing material.

20 In testimony whereof I have hereunto set my hand.

CHARLES F. BUENTE.
